UNITED STATES PATENT OFFICE.

THOMAS B. YETTER, OF FOUNTAIN GREEN, ILLINOIS.

PUMP.

1,182,958.

Specification of Letters Patent. Patented May 16, 1916.

Application filed March 18, 1915. Serial No. 15,219.

To all whom it may concern:

Be it known that I, THOMAS B. YETTER, a citizen of the United States, residing at Fountain Green, in the county of Hancock 5 and State of Illinois, have invented certain new and useful Improvements in Pumps; and I do declare the following to be a full, clear, and exact description of the invention, such as will enable others skilled in the art to which it appertains to make and 10 use the same.

My invention relates to new and useful improvements in pumps and more particularly to those of the reciprocating type used 15 primarily in discharging water from wells.

The object of the invention is to provide a device of this character having a unique arrangement of cylinders, pistons, and valves, whereby with a single reciprocating 20 actuating rod, a continuous flow of water may be discharged.

With this object in view, the invention resides in certain novel features of construction and combination hereinafter described 25 and claimed, one embodiment of the invention being illustrated in the accompanying drawings wherein:

Figure 1 is a side elevation of a portion of a pump constructed in accordance with 30 my invention; Fig. 2 is an edge view thereof; Fig. 3 is a vertical section as seen along the plane indicated by the line 3—3 of Fig. 2; Fig. 4 is a horizontal section taken on the plane designated by the line 4—4 of Fig. 35 3; Fig. 5 is an enlarged vertical section through the upper end of the supplemental cylinder and the parts in conjunction therewith; and Fig. 6 is a detail horizontal section as seen on the plane indicated by the 40 line 6—6 of Fig. 5.

In this drawing, constituting a part of the application, the numeral 1 designates a cup-shaped receiving casing whose lower end is provided with an inlet 2 having an 45 upwardly opening check valve 3, while the top of said casing is provided with a pair of openings in which a main upright cylinder 4 and a supplemental upright cylinder 4' are threaded, the two cylinders being dis- 50 posed in parallel relation and having their upper ends lying in the same horizontal plane. As shown in Fig. 3, these upper ends contact with gaskets 5 and 5' which are carried by annular seats 6 and 6', the latter 55 being formed around the lower sides of a pair of openings with which the bottom 7

of a vertically elongated delivery casing 8 is provided, said casing having in its upper end an outlet from which a delivery pipe 9 leads to the top of the well. 60

For a purpose yet to be explained, the upper end of the supplemental cylinder 4' is closed by an end wall 10 having a central opening which is provided with an upwardly opening check valve 11. Slidably 65 vertically through this check valve is a supplemental piston rod 12' which lies parallel with a main piston rod 12 disposed within the main cylinder 4, both of the piston rods being secured in any appropriate manner 70 to a cross head 13 carried by the lower end of an upright reciprocating actuating rod 14 which rises through the pipe 9 to any appropriate operating means.

Carried by the lower end of the main piston rod 12 and disposed in the main cylinder 4, is a single-acting suction piston 15 having a check valve 16 which opens toward the outlet pipe 9, while disposed in the supplemental cylinder, directly above the piston 17, having a vent pipe 18 whereby air may be allowed to enter the upper end of said cylinder and may be discharged therefrom as the 80 piston 17 is reciprocated.

With the parts constructed as above described, the operation of the device is as follows: Assuming that reciprocation of the rod 14 has previously filled the receiving casing 1 and the lower ends of the cylinders 4 and 4' with water, and that the pistons 15 and 17 are raised, the actuating rod 14 is now forced downwardly, thus causing the piston 17 to force the water beneath it downwardly through the receiving casing 1, upwardly within the cylinder 4, and through the upwardly opening check valve 16. The actuating rod 14 is then moved upwardly, thus lifting the water above the piston 15 while the ascent of both of the pistons draws more water upwardly through the check valve 3. This cycle of operation takes place successively as long as the rod 14 is actuated, it being therefore seen that a steady stream of water will be discharged from the pipe 9. During this operation any water which may leak into the upper end of the cylinder 4' will be again discharged therefrom through the check valve 11, the movement of the latter being limited by a stop 11^a, (see Figs. 3 and 5). 11

Although any appropriate means could be provided for connecting the receiving casing 1 and the delivery casing 8, the two are preferably provided with flanges 20 through 5 which upright tie-bolts 21 pass, as most clearly disclosed in Figs. 1 and 2. Furthermore, although it is not absolutely necessary, it is highly expedient to provide the delivery casing with a hand hole close by a 10 cover plate 22, whereby access may be had into the interior of said casing.

In the foregoing description, I have described certain specified details for reducing the invention to an operative construction, 15 and in the drawings have shown such details, but it will be evident that I need not be limited thereto otherwise than as specified in the appended claims.

I claim:

20 1. A pump comprising a main and a supplemental cylinder disposed side by side and communicating at one end, an inlet into the communicating ends of said cylinders equipped with an inwardly opening check 25 valve, an outlet from the other end of the main cylinder, a single-acting suction piston in said main cylinder and having a check valve opening toward the outlet, a double-acting piston in the supplemental cylinder, 30 and means to reciprocate the two pistons simultaneously.

2. A pump comprising a receiving chamber, a delivery chamber spaced therefrom, an inlet into the former, an outlet from the 35 latter, said inlet being provided with an inwardly opening check valve, a main cylinder between the two chambers and communicating with both of the same, a supplemental cylinder lying parallel to the main cylinder 40 and communicating only with the receiving chamber, a single-acting suction piston in the main cylinder and having a check valve opening toward the delivery chamber, a double-acting piston in the supplemental cylinder, 45 and means to actuate the two pistons simultaneously.

3. A pump comprising a receiving chamber, a delivery chamber spaced therefrom, an inlet into the former, an outlet from the latter, said inlet being provided with an inwardly 50 opening check valve, a main cylinder between the two chambers and communicating with both of the same, a supplemental cylinder lying parallel to the main cylinder and communicating only with the receiving chamber, a single-acting suction piston in the main cylinder and having a check valve opening toward the delivery chamber, a double-acting piston in the supplemental cylinder, 55 a reciprocating cross head in the delivery chamber, and a pair of piston rods leading therefrom to the two pistons.

4. A pump comprising a receiving casing having an inlet provided with an inwardly opening check valve, a delivery casing 65 spaced above the receiving casing and having an outlet in its top, a main upright cylinder interposed between the two casings and communicating with both of the same, a supplemental cylinder rising from the receiving casing to the delivery casing and having its upper end equipped with an apertured under wall, a single-acting suction piston in the main cylinder and having an upwardly opening check valve, a double-acting 70 piston in the supplemental cylinder, a piston rod rising from the double-acting piston through the opening in the end wall of the supplemental cylinder, an additional piston rod rising from the single-acting piston, an 75 upright reciprocating actuating rod rising from the delivery casing through the outlet therein, and connections between the piston rods and said actuating rod.

In testimony whereof I have hereunto set 80 my hand in presence of two subscribing witnesses.

THOMAS B. YETTER.
